UNITED STATES PATENT OFFICE.

GEORGE W. BERNAUER, OF ST. CHARLES, MISSOURI, ASSIGNOR OF ONE-HALF TO J. E. HALLOWELL, OF ST. CHARLES, MISSOURI.

PROCESS OF DRYING SOLUTIONS APPLIED TO KID, LEATHER, OR OTHER MATERIALS.

1,074,346.

Specification of Letters Patent.

Patented Sept. 30, 1913.

Application filed February 8, 1913. Serial No. 747,012.

To all whom it may concern:

Be it known that I, GEORGE W. BERNAUER, a citizen of the United States of America, residing at St. Charles, county of St. Charles, State of Missouri, have invented new and useful Improvements in Processes of Drying Solutions Applied to Kid, Leather, or other Materials, of which the following is a specification.

10 This invention relates to processes or methods of drying solutions applied to leather, kid, calf-skin, or other materials, and has for its prime object to afford a process whereby so-called "patent-leather" or 15 "enameling" solutions can be applied to a finished shoe and very quickly dried thereon without damage to the sole and other parts of said shoe not treated with said solution.

20 In the lasting of shoes made of or comprising patent or enamel leather great trouble has been experienced from the liability of the brittle finish of such leather to crack and from the further fact that the 25 said finish is frequently scratched and otherwise damaged and rendered unsightly during the course of manufacture of the shoe. This necessitates repair before the shoes are merchantable, which is usually accomplished by sandpapering off the enameled surface of the leather until the defects are 30 eliminated, applying a coating of collodion, and next applying one or more coats of liquid enamel, each of said coats being allowed 35 to dry thoroughly before another is applied.

As one long experienced in the art of shoe manufacture I am aware that, prior to my invention, twenty-four to forty-eight hours were ordinarily required for the hardening 40 of the said coats of enamel before the shoes were in fit condition to pack for shipment, which, as will be appreciated, entailed the use of a great amount of space, the expenditure of much labor, and tended to restrict

45 the output of the factory. The difficulty encountered in devising any satisfactory means for quickly drying the refinished leather lay in the fact that, whereas it is well known that patent or enamel leather is

50 commonly produced by baking the same in high-temperature ovens, such a method could not be applied to the problem in hand where the leather had been incorporated in a finished shoe because the heat of the oven—whether the temperature thereof be

high or low—would injuriously affect the sole and other parts of the shoe which were not enameled.

In accordance with the practice of the Patent Office in cases of this character, a drawing is filed herewith illustrating an apparatus by aid of which my process can be carried out, Figure 1 being a top plan view of said apparatus; Fig. 2 a front elevation thereof; Fig. 3 a cross-section along line A—B of Fig. 2; and Fig. 4 a cross-section along line C—D of Fig. 3. However, I wish it understood that said process does not depend for its successful application upon the apparatus shown or any other particular machine.

Referring to the accompanying drawing, in which like numerals refer to like parts throughout the several views, I may employ a box-like receptacle 1 the upper wall of which is provided with a plurality of apertures 2 communicating directly with its interior, said apertures conforming in shape to the toe-portion of a shoe but being slightly less in width and much less in length than the width and length of the shoe. To fuel-supply pipes 3 are connected burners 4 (preferably consisting of a short tube provided with an opening 5) an extremity of which is projected within one end of a combustion chamber 6, the same having a plurality of apertures 7. The opposite extremity of chamber 6 is detachably secured to a tube 8 which is connected with a suction-pipe 9, the latter communicating with the interior of a housing 10 incasing a motor-driven fan (not shown) of any well-known type. Said housing is prolonged into a tube 11 which is coupled with a pipe 12 extending, as does tube 8, from end to end of receptacle 1 and provided with nozzles 13 which are arranged in register with each of apertures 2. Upon the face of said receptacle are secured wire arms 14, adapted to lie on each side of the upper of a shoe to support the same, while the shoe is further retained in proper position by the use of rollers 15 which engage the opposite edges of the sole 15^a.

In operation, the shoe-toes having been 105 coated with the enameling or other desired solution are supported over and fit within apertures 2 as best shown in Figs. 3 and 4, whereby it will be noted that the sole and other parts of the shoe which are not so coat- 110

ed and which it is essential to protect from heat are disposed entirely without receptacle 1. Thereafter, cock 16 being opened the gas supplied by pipes 3 is admitted to burners 4, ignited in combustion-chambers 6 and, the fan having been started, the flame, together with a constant current of air admitted through apertures 7, is drawn through tube 8 and the air so heated carried to said fan by way of pipe 9. From that point said air is blown into tube 11, thence forced along pipe 12 and issues at high temperature from nozzles 13 which direct its flow against the solution, but as apertures 2 are of less width and length than the width and length of the finished shoe, it will be appreciated that they are substantially closed by the insertion therein of the toe-portion of the shoe and that, in consequence, the action of the heated air is restricted to said portion. Obviously, the heat radiated from pipe 8, supplemented by the action of the blast from said nozzles, serves to rapidly dry and harden the solution and in actual practice under the usual factory conditions I have demonstrated that but an hour or less is required

under this process to produce results which have heretofore required many hours.

What I claim as new and desire to secure by Letters-Patent is:—

1. The method of drying and hardening solutions applied to shoes which comprises the disposition of the part carrying the solution within a heated receptacle, simultaneously disposing the portions of the shoe not treated with the solution without said receptacle, and restricting the action of the heat to said part.

2. The method of drying and hardening solutions applied to shoes which comprises the disposition of the part carrying the solution within a heated receptacle, forcing a blast of air against said part, simultaneously disposing the portions of the shoe not treated with the solution without said receptacle, and restricting the action of the heat and blast to said part.

GEORGE W. BERNAUER.
